JOHN EDWARD REAVES AND CLAUDE MARION BANDY, OF SACRAMENTO, CALIFORNIA.

SECURING DEVICE FOR TAPPETS.

1,124,661.

Specification of Letters Patent.

Patented Jan. 12, 1915.

Application filed June 7, 1913. Serial No. 772,358.

To all whom it may concern:

Be it known that we, JOHN E. REAVES and CLAUDE M. BANDY, citizens of the United States, residing at Sacramento, in the county 5 of Sacramento and State of California, have invented certain new and useful Improvements in Securing Devices for Tappets, of which the following is a specification.

The hereinafter described invention relates 10 to certain new and useful means for locking the tappet in adjusted position relative to the stamp stem of a stamp mill and hold the same in such locked position and against displacement relative to the stamp stem during 15 operation of the stamp mill, the construction and operation of the locking means being such as to permit of the tappet being readily released from the stamp stem to vary the position thereto in accordance with 20 the wear action of the stamp head; the object of the invention being to prevent the slippage of the tappet on the stamp stem under the influence of the impact strains to which it is subjected during the operation 25 of the stamp mill, while at the same time providing a simple, effective and durable form of locking means which will do away with driving keys ordinarily employed for locking the tappet to the stamp stem, and 30 allow of the tappet being quickly released from the stamp stem for purpose of adjustment.

To comprehend the invention, reference should be had to the accompanying sheet of 35 drawings, wherein—

Figure 1 is a broken view in elevation of a stamp stem with the tappet applied thereto, illustrating the tappet cam for raising the stamp stem through the medium of the 40 tappet. Fig. 2 is a vertical sectional view of the tappet, disclosing the means for holding the same locked to the stamp stem. Fig. 3 is a cross sectional top plan view taken on line $x-x$, Fig. 2 of the drawings.

45 In the drawings, the numeral 1 is used to designate a stamp stem provided with the usual stamp head 2, to which stem the tappet 3 is secured by the hereinafter described locking means. The tappet is acted on by 50 the ordinary tappet cam 4 for raising the stamp head 2, as usual in connection with stamp mills, the said cam being mounted on the cam shaft 5. Within the tappet is provided a vertically disposed countersunk seat 55 6, which communicates with the central bore 7 of the tappet, and in said seat is fitted a

gib 8. The outer face of the gib 8 is shaped to conform to the surface of the stamp stem 1 which it frictionally engages, and on the inner face of the said gib the inclines 9 and 9' are formed. These inclines are engaged by the inclined wedges or locking keys 10 and 10', which fit within the transverse key seats 11 and 12 formed in the tappet 3—Figs. 2 and 3 of the drawings. These keys 10 and 10' serve to wedge the gib 8 in position and hold the same and the tappet 3 securely to the stamp stem 1, it being obvious that the farther the said keys are driven into the key seats, the firmer will become, 70 through the tightening or wedging of the gib 8, the locked union of the tappet 3 to stamp stem 1.

In securing the tappet to the stamp stem, the gib 8 is first placed into its seat 6 within 75 the tappet 3 and the tappet then fitted onto the stamp stem until properly positioned relative to the tappet cam 4. The keys 10 and 10' are then fitted respectively into the transverse seats 11—12, when during opera- 80 tion of the stamp the blow of the cam 4 against the under face of the tappet forces the said tappet upwardly, causing the gib to tighten against the stamp stem by reason of the keys 10 and 10' acting against the in- 85 clines 9 and 9', which wedges the said gib firmly against the stamp stem, and by so doing holding the tappet securely locked thereto. As thus locked, it is obvious that during operation of the stamp mill the im- 90 pact blow or strain imparted or transmitted to the tappet and tending to move the same upwardly on the stamp stem, tends to increase the wedging action of the gib 8 relative to the stamp stem and by so tighten- 95 ing the tappet relative to the stamp stem and thus increasing the friction union between the said parts.

Where it is desired to release the tappet for purpose of adjustment, it is only required to strike a blow downward on the tappet with a hammer, in order to loosen the gib 8, when the tappet is free to be moved up and down on the stamp stem to adjust the same to any desired position, which adjustment is required to regulate the throw of the stamp stem in accordance with the wear of the stamp head.

While we have illustrated and described the preferred form of frictional locking 110 means for adjusting and holding the tappet locked relative to the stamp stem, we do not

wish to be understood as limiting or confining ourselves to the described detailed construction as to the coöperating working parts.

5 Having thus described the invention what we claim as new and desire to protect by Letters Patent is:—

1. A means for securing a tubular member to a shaft, the same including a tubular member through which the shaft passes, said member being provided with an internal seat and transversely disposed key ways, a clamping member loosely fitted within the internal seat of the tubular member and provided on its rear face with transversely extending key seats, the face of both of said seats being beveled in a corresponding direction and toward one end of said clamping member, and wedge shaped keys formed with 10 a transversely beveled and longitudinally extending front face and movable within the key ways of the tubular member for engagement with the beveled key seats of the clamping member for forcing the same into 15 frictional engagement with the shaft to lock the tubular member thereto.
- 20 2. A means for securing a tubular mem-

ber to a shaft, the same including a tubular member through which the shaft passes, said member being provided with an internal seat and transversely disposed key ways having a longitudinally inclined rear wall, a clamping member loosely fitted within said internal seat and provided on its rear face with key seats, the rear faces of both 30 of which are beveled in a direction toward one end of said clamping member, and tapering keys formed with a substantially flat rear face for contact with the inclined rear wall of said key ways and formed for their full length with a transversely beveled longitudinal inclined front face for coöperation 35 with said beveled key seats in the clamping member for forcing the clamping member into frictional engagement with the shaft to lock the tubular member thereto.

40 In testimony whereof we have signed our names to this specification in the presence of two subscribing witnesses.

JOHN EDWARD REAVES.
CLAUDE MARION BANDY.
